UNITED STATES PATENT OFFICE

FRANK D. SAYLOR, OF DETROIT, MICHIGAN

CIRCULAR LOOM

Application filed January 17, 1930. Serial No. 421,380.

The present invention relates to looms or machines for weaving tubular fabric and more especially, to safety devices for the same.

5 Among the objects of the invention is to provide means to reduce the supervision required when such machines are operating by providing automatic means to stop the mechanism upon breaking of a weft strand.

10 Other objects will readily occur to those skilled in the art upon reference to the following description and the accompanying drawings in which:—

15 Fig. 1 is a plan view of the machine with parts omitted for clearness;

Fig. 2 is a vertical section on line 2—2 of Fig. 1;

Fig. 3 is an enlarged view, partly in section, of the shuttle moving means;

20 Fig. 4 is a plan view of one of the shuttle members;

Fig. 5 is a view as from line 5—5 of Fig. 4;

Fig. 6 is a sectional view taken on line 6—6 of Fig. 2.

25 Fig. 7 shows a detail of the machine.

As indicated in the drawings, the loom is constructed with a circular frame 10 comprising a base portion 11 and cylindrically arranged uprights 12, adapted to support the moving parts.

30 Mounted on base 11, is a shaft 13 carried in suitable bearings, not shown, which shaft has keyed thereto a gear 14 which may form part of a sleeve 15 which carries a pulley 16. Also carried on shaft 13 is an idler pulley 17.

35 Fixedly centrally on the base 11 is a vertical tube 20 which serves as a fixed shaft about which rotates the frame member 21.

40 This member 21 is supported on the base 11 by a suitable anti-friction bearing 22 and includes an outwardly extending portion 23 having at its outer edge a downwardly extending cylindrical part 24 in whose outer surface is a pair of slots 25 for a purpose to be mentioned later. The bottom edge of portion 24 is provided with a ring gear 26 which coacts with the gear 14 to drive the 45 member 21.

50 Located above the part 23 of member 21 is a second outwardly extending frame portion 30 carrying on its upper side a pair of small frames 31, each having bearings 32 for shafts 33. The shafts 33 have at one end 55 a small wheel 34 and at the other end a second wheel 35.

55 The frame 31 and its associated parts is shown in enlarged view in Fig. 3. This figure shows that one of the bearings 32 for shaft 33 consists of a bearing part 32a mounted as a plunger in the inner end of the frame and supported by a spring 32b so that the shaft 33 and the wheel 34 will be spring 60 pressed upwardly.

65 Also carried on the hollow shaft 20 is a head member 40 which has on the under side of its periphery a track 41 for wheel 34 and against which the wheel 34 is spring pressed, as is mentioned above.

70 This head member 40 furnishes support on the upper side of its periphery for the small wheels 42 which will be more particularly described later.

75 The upper end of the shaft 20 is open and may have fixed therein a hollow mandrel 43 serving as the outside form for the tubular product which passes down through the shaft 20 to a suitable receiver, and fixed above the upper end of the tube is a small frame 44 carried upon an arm 45 suitably supported by the outside frame 12. This arm carries an inside mandrel 46, whose lower end extends down into the tube 20 and serves as the inside form for the tubular product.

80 This frame member 44 is provided at its lower edge with a track portion 47 which overlies the small wheels 42 hereinbefore mentioned.

85 Carried by the outer frame 12 is a fixed upright cylindrical member 50 having a plurality of vertical slots 51 through which slots extend the warp cords 52, each of these cords extending from a suitable reel, not shown, through an eye 53 on the side of the frame and through a second eye in a guide rod 54. From the rod 54, the cords extend each through an eye 53' in a heddle 55, which heddle passes through a suitable opening in member 50 and has at its lower end a small 90

100

roller 56 adapted to travel in one of the grooves 25. The grooves 25 are so arranged that they cross each other at suitable intervals. Consequently, when member 23 is rotating, each heddle will alternately move up and down and will move up as an alternate heddle moves down.

Within the member 50 are two shuttle members 60 which are moved around the center 10 of the machine and supported on the small wheels 42 near the center and large horizontally placed wheels 61 adapted to travel in a suitable groove 62 in member 50. Each one of these shuttle members 60 has at one end 15 near the member 50a small wheel 63 which extends beyond the shuttle frame 64 so that it may coact with the wheel 35, which is carried by shaft 33, as shown in Fig. 3. The wheel 35 is so located with respect to wheel 63 that as the frame 31 is carried around the center of the machine, this wheel 35 pushes the shuttle around with it and as the frame 31 is carried around shaft 20, the small wheel 34 coacts with its track on the head member 20 40 so as to rotate and in rotating revolves wheel 35.

As the member 23 is carried around by the gear 26 the heddles move up and down in their proper order and the shuttle passes under each alternate warp cord 52 and over the intermediate cords due to the changing of the position of the cords by the heddles. The wheel 35 rotating against wheel 63 and moving the shuttle in its circular path will easily and without danger to the cord, roll it up between the two wheels, as the shuttle passes, this being due to the fact that the wheels 35 and 63 rotate in such directions that their peripheral surfaces adjacent their point of contact move upwardly as the wheels rotate.

Each shuttle 60 carries thereon a reel 70 which contains the weft material and allows it to be pulled out to the weaving position at the mandrels 43 and 46.

As the weft material 71 is drawn from the reel, it passes over two pins 72 and 73 and behind an intermediate pin 74. The intermediate pin is in fixed position upon the shuttle frame while the two pins 72 and 73 are carried by an arm 75 pivoted at 76 on the frame, both pins being on the same side of the pivot. The arm is extended beyond the pivot 76 and has at its other end a shoe member 77 which has secured thereto a spring 78 secured at its other end to the frame 64 in such position as to move the arm 75 to bring the pins 72, 73 and 74 out of alignment and pull the shoe 77 to the dotted line position shown in Fig. 4. So long as sufficient tension is applied to the end 71a of the weft material, that is, so long as the weaving operation is being conducted satisfactorily with a continuous drawing of the weft material from the reel 70, the tension on this material will maintain the pins 72, 73 and 74 in substan-

tial alignment and the shoe 77 in approximately the position shown in full lines in Fig. 4. However, if the weft material breaks and thereby tension is taken from it, the spring 78 will immediately pull the shoe 77 to the dotted line position in Fig. 4 and this shoe will then set in motion the following described mechanism to stop the machine.

Mounted on the portion 50 of the frame is a horizontal shaft 80 which has at its outer end a handle 81 serving to permit manual movement of the shaft and having at its inner end a short vertical shaft 82 secured to shaft 80 by means of a suitable fitting 83. When the shoe 77 swings to the dotted line position of Fig. 4, it strikes the end of shaft 82, and thereby causes a partial rotation of shaft 80 in a counter-clockwise direction, assuming the observer to be at the right of Fig. 2 and the shuttles to be moving counter-clockwise (Fig. 1).

When the shaft 80 is moved as indicated the projection 85 carried thereby is moved from behind a cooperating projection 86 carried by a horizontally movable arm 87 carried by or formed upon the upper end of a vertically arranged shaft 88. This shaft 88 has near its lower end a second horizontal arm 89 connected to a longitudinally movable rod 90, carrying a belt shifting fork 91, and slidably in a suitable guide 92. A second guide and abutment 93 serves as a stop member for the fork and between this and a suitable collar 94 is placed a spring 95 arranged to be under compression when the belt 96 is on pulley 16. When, therefore, the weft material 71 on a shuttle breaks, the shoe 77 moves out and strikes shaft 82 releasing arm 87 and allowing the belt to be shifted, through the expansion of spring 95, to the idler pulley 17.

The present application is a continuation in part of previously filed Patent No. 1,775,325, Sept. 9, 1930, on Safety devices for looms.

Now having described the invention and the preferred form of embodiment thereof, it is to be understood that the said invention is to be limited, not to the specific details herein set forth, but only by the scope of the claims which follow.

I claim:

1. Circular loom comprising a central mandrel, shuttles adapted to be moved around said mandrel, supporting and driving wheels on each shuttle, and means for moving said shuttles around said mandrel, said means comprising a driving member having mounted thereon radial shafts each carrying a wheel adapted to contact with the driving wheel of a shuttle and each likewise carrying a second wheel located radially inward of the first and a stationary track located above said second wheel and with which said second wheel contacts, whereby to cause said shaft to rotate axially in a direction opposite to

normal as the shafts rotate orbitally around the mandrel when said driving member is actuated, one of the supporting wheels of the shuttle resting on the upper surface of said

5 track.

2. In a circular loom, the combination of a main frame having a central mandrel around which a shuttle may be revolved, a driving means, a stationary member, a friction wheel, a pushing wheel mounted on a shaft which is driven by said friction wheel, said friction wheel being mounted on a portion of the driving means and held in contact with the stationary member by a light

15 spring.
